UNITED STATES PATENT OFFICE

91,776

DESIGN FOR A LAMP

Edward C. Godfrey, Detroit, Mich.

Application December 23, 1933, Serial No. 50,203

Term of patent 14 years

To all whom it may concern:

Be it known that I, EDWARD C. GODFREY, a citizen of the United States, residing at Detroit, county of Wayne, State of Michigan, have invented a new, original, and ornamental Design for a Lamp, of which the following is a specification, reference being had to the accompanying drawing forming part thereof.

Figure 1 is a perspective view of a lamp, show-

ing my new design, as it appears in position for use upon a table; and

Figure 2 is a perspective view thereof upon a smaller scale, showing my new design as it appears in position for use as a wall lamp.

I claim:

The ornamental design for a lamp as shown.

EDWARD C. GODFREY.
